UNITED STATES PATENT OFFICE

WILLIAM D. CRAIG, OF MEADVILLE, PENNSYLVANIA, ASSIGNOR TO HOOKLESS
FASTENER COMPANY, A CORPORATION OF PENNSYLVANIA

GARMENT

Application filed March 4, 1930. Serial No. 433,053.

My invention relates to garments or the like and particularly to corsets or corselets having improved fastening means for holding the corset in position on the body of the wearer.

5 An object of my invention is to provide an improved construction of garment or similar article having an initial fastening means and a second independent fastening device to be connected after fastening of the initial fastening means.

Slide fasteners have now come into wide use in a large variety of articles including footwear, clothing, luggage, handbags and containers of all kinds. While such fasteners were at first made only with the fastener stringers permanently connected together at one end, they are now manufactured in both this form and also equipped with a separable 15 end connection whereby the fastener stringers and the portions of the articles to which they are attached, may be completely separated from each other. This has considerably widened the field for the advantageous use of slide fasteners. Many earlier attempts have been made to place this improved fastening device in corsets and corselets, but up to the present time, such attempts have not met with any great commercial success. 20 When it is attempted to apply the fasteners to corsets various difficulties are encountered and it is found that the service imposed on a slide fastener as heretofore applied is more difficult than in almost any other of the large 25 number of uses to which it is applied. One of the reasons for the difficulty which has been heretofore experienced with slide fasteners in corsets is due to the fact that the fastener by reason of its construction, must first 30 be connected at one end and then the fastener elements brought together and interlocked by the slider progressively from the connected end to the other end. After connecting the fastener stringers at one end it has been 35 found that the remaining portions of the stringers are so far apart and that the fastener must frequently be closed under such strain to stretch the corset around the body, that it is almost impossible to move the slider 40 to close the fastener.

My invention, therefore, aims to overcome the above difficulties in a novel and satisfactory manner. In carrying out the invention the corset is stretched to position around the body and held by an initial fastening device, 55 which serves to position the fastener stringers adjacent each other so that they may be more easily closed by the action of the slider. In order that the initial fastening device may be easily connected by the wearer and serve 60 its purpose effectively, a strap or plurality of straps are attached to the inner surface of the corset on one side and extend free from the body of the corset so that the wearer can easily grasp the strap and connect it to the fastening device on the opposite side. 65

In the preferred embodiment of the invention a single fastening device such as a hook and eye is employed with one part attached to a strap as mentioned above and the other 70 part carried by a flap, which is designed to distribute the stress over the entire length of the corset so as to position the fasteners approximately parallel and adjacent to each other along their entire length. 75

A more specific object therefore is to provide an improved construction of corset or the like, which preferably embodies one or more elastic sections, in which a single initial fastening device is employed at about the line 80 of resultant stress on the corset, in conjunction with a fastener of the type having fastener elements adapted to be progressively interlocked from one end to the other of the fastener stringers. 85

Other objects and advantages will more fully appear during the course of the following specification.

In the accompanying drawing I have 90 shown for purposes of illustration, my invention embodied in a garment, the particular style of which is known as a girdle. In the drawing:

Fig. 1 is a front view of a girdle embodying 95 my invention with one edge of the girdle turned back to facilitate illustration.

Fig. 2 is a view similar to Fig. 1 showing the fastener stringers in position to be fastened. 100

Fig. 3 is another view similar to Fig. 1 showing the girdle as fastened.

Fig. 4 is a view of the inside of the front section of the girdle.

Fig. 5 is a detail view showing one end of the slide fastener on an enlarged scale.

Figs. 6 and 7 are detail views illustrating different forms of the initial fastening device on an enlarged scale.

The improved girdle as illustrated, embodies a body encircling member 7 having elastic sections 8 and 9 of substantial width on opposite sides which are connected by a section of suitable fabric material (not shown) in the back of the girdle. On the 10 left side of the girdle as illustrated in Figs. 1, 2 and 3, a front fabric section 10 is stitched to the elastic section 8, and has on its other vertical edge a slide fastener stringer 11 which may be attached in any desired manner, preferably by stitching. A cooperating 15 fastener stringer 12 is attached to the opposite separable portion of the girdle, preferably by stitching directly to the elastic section 9, although of course, another fabric section 20 may be arranged between the elastic section and the stringer. If desired, any suitable vertical stiffening means may be employed, many types of which are well-known in the art. A pair of garter supporters 13 are 25 shown depending from the front fabric section 10.

The fastener stringers 11 and 12 comprise parts of a slide fastener of a well-known type 30 shown in the patent to Gideon Sundback No. 1,219,881, March 20, 1917. The fastener embodies cooperating series of fastener elements 14 and 15 attached to the adjacent longitudinal edges of the stringers 11 and 12 respectively, which are adapted to be brought together at an angle to each other and progressively interlocked by means of a slider 16. The slider is actuated along the stringers to effect engagement or to release the fastener 35 elements by means of a pull member 17. At their upper ends as best illustrated in Fig. 5, the stringers are separably connected by an end connecting device comprising a socket 18 clamped on opposite sides to the stringer 11, 40 and a pin member 19 on the stringer 12 which is received in the socket 18. When the fastener is completely disconnected and it is desired to reconnect it, the pin member is threaded through the slider and the socket 18 45 into engagement with the stop lug 20 whereby the fastener elements 14 and 15 are correctly aligned for proper engagement by the slider. The edge 21 of the socket member acts as a stop for the slider and prevents its 50 movement off of the stringer 10 and also positions the slider correctly during insertion and removal of the pin member 19. At the other ends of the stringers are stop members 55 22 and 23 which engage each other inside the slider and limit its downward movement.

At a point spaced a substantial distance from the outer free edge of the front fabric section 10, there is connected one or more flexible straps. In the present instance a pair of such straps 24 and 25 are employed, the 70 strap 24 being connected at a suitable point spaced from the top and the other strap 25 being connected near the bottom. These straps meet at a common point at about the hip line of the girdle so that the initial fastening is disposed at about the resultant line of stress on the girdle. It will be understood that the straps are attached in any suitable manner such as by stitching to the inner side of the girdle as indicated in Fig. 4 at 26 75 and 27. On the opposite side a flap 28 of a generally triangular shape is connected to the elastic section 9 so as to underlie the fastener stringer 12. The apex of this triangular shaped flap is located along the hip line, and the initial fastening device connects the straps 24 and 25 and the flap at this point so as to hold the elastic sections 8 and 9 under tension and position the fastener stringers 11 and 12 adjacent each other 80 as illustrated in Fig. 2. Such initial fastening device may be of any common form but preferably comprises a hook 29 carried by the straps 24 and 25 and an eye 30 attached to the flap. Special attention should be given to the construction of the flap 28 so as to have the stress distributed evenly from the initial connecting device 30 to the entire edge 85 of the elastic section 9. This flap is preferably constructed of one or more layers of 90 substantially inelastic hard woven material secured together by lines of stitching. I have found in practice that a material known as coutil will serve the purpose very well. A modified construction of this flap is illustrated in Fig. 4 where the flap is made up 95 of two layers of material 31 and 32 between which are secured a series of straps 33 which radiate from the apex of the flap to different portions of the opposite edge. These 100 straps will thus serve to distribute the stress along the entire edge of the flap although it is believed that if a proper material is used the straps will not be required. When the fastener is connected it will be observed that 105 the flap underlies the metal fastener elements, separating end connection and slider so as to prevent contact of the metal parts with the wearer. If desired, an eyelet 34, illustrated in Fig. 7 may be used in place of the 110 eye 30.

In the use of the girdle embodying my invention, it is placed in proper position on the body and the wearer takes hold of the strap or straps 24 and 25 on one side and the flap 28 on the other side allowing the free portion of the front fabric section 10 to swing outwardly, and the girdle is pulled around the body so as to stretch the elastic sections 8 and 9. During this operation the separable 115 120 125

edges are pulled outwardly toward the front of the body and thus the elastic sections can be stretched over their entire area because they are not being held tightly against the body. The hook and eye are then connected

5 whereby the parts are held in tensioned condition. The front fabric portion is swung into position as illustrated in Fig. 2 and the slide fastener is now ready to be connected.

10 The slider 16 is moved to the upper limit of its travel and the pin 10 is threaded through the slider into the socket 18 and against the stop 20. The slider can now be pulled downwardly to close the fastener and it will be seen that with the stringers positioned closely adjacent each other, the final closing operation becomes an easy matter.

15 The elastic sections need be stretched only a slight amount more in order to interlock the fastener elements which can be very easily

20 accomplished by the slider. When the slide fastener is closed it will be noted that all tension is removed from the straps 24 and 25 and the hook and eye 29 and 30. There

25 will therefore be practically no danger of these parts failing in service. A locking type of slider is preferably employed so that there will be no tendency for the slider to work upwardly and allow the fastener

30 to open.

As a result of my invention it will be apparent that an improved garment or the like has been devised in which a fastener of the slide operated or similar type may be used 35 to great advantage. The principal difficulties which have been encountered in the use of slide fasteners in corsets, girdles and corselets have been overcome by my invention.

40 While I have in this application specifically described one type of garment and one or more embodiments which it may assume in practice, it will be understood that the invention is adapted to all types of corsets, 45 girdles and corselets as well as other articles where a similar problem is involved, and may be embodied in various other forms without departing from the scope of my invention which is defined in the following 50 claims.

What I claim as my invention is:

1. A garment comprising a body encircling member having separable edges, a slider operated fastener having cooperating series of 55 fastener elements along said separable edges, and a slider movable along said elements for engaging or disengaging the same, a flap underlying said fastener elements on one side and projecting beyond said elements, a strap 60 attached to the under side of the garment on the opposite side and independent fastening means on said flap and strap adapted to be initially fastened to place the garment under tension and to position said edges adjacent 65 each other to facilitate closing movement of

said slider and prevent catching of the slider on the fastener elements during closing, said slider operated fastener, when closed, being adapted to remove the stress from said independent fastening means.

2. A corset or the like, comprising a body encircling member having separable vertical edges said member including a section of elastic material adjacent to one of said edges enabling said member to be stretched around 70 the body, fastening means for said corset comprising a slider operated fastener having cooperating series of fastener elements along said vertical edges for uniting the same, a slider movable along said elements for engaging or disengaging the same, a separable end connection comprising separable parts attached to said edges at one end of said series of elements, a flap attached to one of said edges and projecting therefrom under 80 said slider operated fastener, a strap attached to the opposite side of the corset, and a separable fastening device for connecting said strap to said flap at about the hip line of said corset, and when connected, being adapted 85 to maintain said elastic sections stretched and to position said edges of the corset adjacent each other to enable the slider to be more easily moved in closing the fastener and to prevent catching of the slider on said fastener elements.

In testimony whereof I affix my signature.
WILLIAM D. CRAIG.
